PERMANENT WAVE CLIP
James W. Erb, Box 596, Battle Creek, Mich. 49017
Filed July 5, 1966, Ser. No. 562,708
4 Claims. (Cl. 132—40)

This invention relates to hair curlers and similar devices, and more particularly an improved permanent wave clip.

It is therefore the main purpose of this invention to provide an improved permanent wave clip adapted to provide permanent waves on hair which is of uneven length.

Another object of this invention is to provide an improved permanent wave clip which is adapted to roll hair from the center or upper portions, unlike the devices of the prior art which are adapted to grip the hair at the scalp only.

Another object of this invention is to provide an improved permanent wave clip which is designed for self combining action during the gripping and rolling operation.

Still another object of this invention is to provide an improved permanent wave clip which is of simple construction, inexpensive to manufacture, may be moderately priced, being constructed of materials or coated with a chemical compound which does not react or is effected by the permanent wave solution, and provides maximum utility to its user.

Other objects and advantages of this invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing:

FIGURE 1 is a side elevation of this invention shown partly broken away.

FIGURE 2 is a top plan view of FIGURE 1.

FIGURE 3 is an end view of the main body shown in FIGURE 1.

According to this invention, an improved permanent wave clip 10 is provided with a main clip body or rod 11 assumes generally elongated configuration. One end of rod 11 is designated as a guiding portion 12 which assumes a sharpened contour for inserting rod 11 into the hair. An elongated aperture 13 is provided within said rod for providing securing means to the auxiliary clip 17. The outer portion 14 of rod 11 is provided with a stationary, elongated clip 15 which is permanently secured thereto at 16.

2

Looking now at the drawing, one will see that the external clip portion 18 of the auxiliary, removable U-type clip 17 may be suitably inserted to or removed from the aperture 13 in accordance with the operational requirements. An elongated, external clip portion 19 is spaced from the rod 11 so that gripping means is provided for the rolling of hair.

It will also be noted that, in operation, the strands of hair are placed between the stationary clip 15 and rod 11. Then the other portion of same hair are suitably positioned between the external clip portion 19 and said rod 11. Then the clip 10 is rotated in a clockwise or a counter-clockwise direction. Once hair solidifies, that is, assumes the characteristics of a permanent wave, the auxiliary clip 17 is disengaged or removed from rod 10. This makes the subsequent removal of the remaining rod 11 somewhat easier.

What I now claim is:

1. An improved permanent wave clip comprising, in combination, a substantially elongated rod including an elongated aperture therein, a sharpened end portion extending outwardly from said rod for guiding said permanent wave clip during the hair curling operation, an elongated stationary clip permanently attached to one side of said rod for securing a portion of hair between said stationary clip and said rod, a U-shaped auxiliary clip, one end of said clip being removably positioned within said aperture of said rod for providing supplemental securing means for hair located between the external portion of said auxiliary clip and said rod.

2. The combination according to claim 1, wherein a grasping means is provided on said stationary clip for inserting said permanent wave clip into the hair.

3. The combination according to claim 1, wherein said stationary clip is positioned in a parallel relationship to said rod and one end of said stationary clip is bent for providing an air gap therebetween.

4. The combination according to claim 1, wherein the end portions of said auxiliary clip are of elongated configuration and are positioned to each other in a parallel relationship.
